UNITED STATES PATENT OFFICE.

MORRIS B. OKUN, OF CHICAGO, ILLINOIS.

BED-RAIL FASTENING.

1,083,938.

Specification of Letters Patent.

Patented Jan. 13, 1914.

Application filed August 1, 1913. Serial No. 782,443.

To all whom it may concern:

Be it known that I, MORRIS B. OKUN, a citizen of the United States, residing at Chicago, in the county of Cook and State 5 of Illinois, have invented new and useful Improvements in Bed-Rail Fastenings; of which the following is a specification, reference being had to the accompanying drawings, forming a part thereof.

10 The purpose of this invention is to provide an improved construction for fastening the longitudinal rails of a bed to the corner posts, which may be adapted for securing the cross rails to the longitudinal rails.

15 It consists in the elements and features of construction shown and described, as indicated in the claims.

20 In the drawings: Figure 1 is a perspective view from the outer side of the corner of a bed frame embodying this invention in service on the corner post. Fig. 2 is a perspective view of the same from the inner side. Fig. 3 is a view similar to Fig. 2, showing the side rail in reverse position. Fig. 4 is a longitudinal vertical section at the line, 4—4, on Fig. 1. Fig. 5 is a section at the line, 5—5, on Fig. 4. Fig. 6 is a perspective view of a staple-like element which 25 constitutes a member of the bracket housing and assists in securing it to the corner post. Fig. 7 is a perspective view from the inner side of said bracket housing without the member shown in Fig. 6. Fig. 8 is a plan view of the blank from which one member 30 of the bracket housing is formed by folding and joining. Fig. 9 is a plan view of a blank from which the staple-like member of the housing is formed. Fig. 10 is a partly 35 sectional detail view of a swiveled nut and sleeve in the locking device.

40 This invention, as illustrated in the drawings, comprises a bracket housing, A, for receiving the tongue, 2, of a bed side rail, B, for junction with the corner post, C; the bracket housing being secured to the corner post as will hereinafter be described. Said bracket housing, as illustrated, comprises a member, 1, which constitutes the 45 housing proper, and a staple-like device, 3, which assists in securing the bracket housing as a whole to the corner post, and also affords an end bearing for the side rail tongue, 2. The member, 1, is made of metal plate which is first cut in the form of the blank shown in Fig. 8, having afterward

the lugs, 1^a, folded out at right angles to the plate so as to extend parallel for engagement with the post, as hereinafter described, and having the sides, 1^c, 1^d, also folded at 50 right angles to the plane of the plate, but in opposite direction from the lugs, 1^a, to form parallel vertical sides of the housing. The end portion of the side, 1^d, is folded inward at right angles thereto toward the 55 opposite side, 1^c, forming the inner end, 1^e, of the housing which is secured by the projections, 1^f, protruded through and riveted upon the opposite side, 1^c. The member, 3, of the bracket housing, is made by folding 60 up the blank shown in Fig. 9, so as to form a "box" of which the two ends, 3^a, 3^b, project farther than the sides, 3^b, said ends, 3^a, thus forming lugs which are spaced from 65 each other a distance sufficient for embracing between them the lugs, 1^a, 1^a, of the member, 1, when the box-like staple-like member, 3, is positioned between the two sides, 1^c, 1^d, of the member 1, the latter being of such dimensions between its said sides 70 75 as to admit said staple-like member. When the two members are assembled as described, key apertures, 4 and 5, in the upper and lower lugs, 1^a, 1^a, respectively, coincide with similar apertures, 6 and 7, in the upper and 80 lower lugs, 3^a, 3^a, respectively, to receive a tapered key, D, which may be inserted up 85 through said apertures inside the post, C, after the bracket has been applied to the post by inserting the lugs, 1^a, 3^a, through the 90 apertures, C¹, C¹, of the post.

95 The apertures, 5 and 7, in the lower lugs of the two members, 1 and 3, are longer than the apertures, 4 and 6, in the upper lugs to suitably accommodate the tapered key 100 driven in from below. Said key is prevented from escaping, in case it should be jarred loose, by means of a guard device, E, which consists of a piece of sheet metal having an aperture, E¹, adapting it to be hung upon the lower lugs, 1^a, 3^a, after they are inserted through the post and before the key is applied. After the key is forced up into tight position, the lower end of the retaining device, E, may be bent at right angles to its 105 plane so as to extend past the lower end of the key to stop the same against dropping. The sheet metal is of such character as to be readily bent back to permit the removal of the key. This key-retaining device is substantially the same as shown in my pending application No. 741,674, filed January 23,

1913, and is not claimed in this application. The forward or inner vertical edge wall of the housing has an aperture, 9, the outer vertical edge of which is in the vertical plane 5 of the inner surface of the outer side wall, 1^c, of the housing C so that the tongue, 2, of the bed side rail, B, when inserted into the housing, lies flat against the inner surface of the outer side wall of the housing. The 10 bottom web of the "box" of the staple-like member, 3, of the housing has a corresponding aperture, 10, for receiving the inner end of the tongue, 2, this aperture, 10, being cut so as to involve, but not extend entirely 15 across, so as to cut in two, the outer side flange or wall of the "box" of said staple-like member, 3, and the inthrust of said tongue, 2, is stopped by the end of said aperture, 10, in the side wall of said box.

20 At a position in the housing member, 1, intermediate the vertical edge wall, 1^c, and the bottom of the box of the member, 3, there is mounted in said housing member, 1, a stud, 12, which protrudes across the housing 25 at a position near the path of the lower edge of the tongue in its inthrust into the housing and its position when engaged therein. This stud is inserted through the outer wall of the housing and is adapted to be rigid there- 30 with against rotation, by having a square shoulder, 12^a, next to its head, 12^b, which is stopped against the outer side of the housing wall, the latter having a square aperture, 1^c, to receive said shoulder. On this stud there 35 is mounted for sliding longitudinally thereof, a sleeve, 13, which is conically tapered at the inner end, the remainder of its length being cylindrical. The end of the stud which extends outside the housing is 40 threaded to receive a wing nut, 14, which being screwed up onto the stem operates to crowd the sleeve along the stud, forcing its inner tapering end under the edge of the tongue, 2, when the latter is in position in 45 the housing and crowds it tightly up against the upper ends of the apertures, 9 and 10, through which said tongue is thrust for its engagement with the housing. The tongue is thereby bound tightly in position. To 50 further prevent it from being withdrawn endwise, the tongue is preferably provided with a notch, 15, positioned in its edge so as to be engaged by the tapering sleeve when the latter is thrust along the stud, as de- 55 scribed. The inner wall, 1^c, of the housing has the aperture through which the stud, 12, protrudes large enough to permit the introduction of the sleeve, 13, onto the stud through said aperture into the housing, the 60 sleeve being thus afforded a bearing on the said inner wall and extending outward beyond the same. Preferably the nut, 14, is engaged with the sleeve for moving the latter longitudinally but so as to permit free 65 independent rotation of the nut and sleeve

on the stud. A convenient method of providing for such engagement and permitting such freedom of relative rotation is illustrated, consisting in providing in the periphery of the sleeve, at its cylindrical portion and near its outer end, an annular groove, 13^b, and forming the nut, 14, with a skirt or cylindrical flange, 14^a, adapted to encompass the end of the cylindrical portion of the sleeve far enough to overhang the groove, 13^b, and two pins, 14^b, are driven through the skirt or flange into the groove for rigid engagement with the skirt or flange, and a loose engagement with the groove.

• The side rail, B, is preferably, as shown, of angle iron, having the tongue, 2, secured to the vertical flange. Both ends of the rail being similarly provided with a tongue, and both edges of the tongue having a notch, 15, it will be seen that the tongue, 2, being longitudinally symmetrical, and each end of the rail being similarly provided with such a longitudinally symmetrical tongue, and the two tongues being precisely similar in manner on the two ends respectively of the rail, the rail may be reversed end for end and edge for edge, so as to be engaged either side up, that is, with the horizontal flange either at the top or at the bottom of the rail, 90 but, in either case, projecting inward. This adapts the rail to support string frames or other mattress supports of different types, both those which might be entered between the vertical flanges of the two opposite side 10 rails and lodged upon the horizontal flange projecting from the bottom of the rail, and those which might be too wide to be thus entered between the vertical flanges of the opposite side rail, but could be properly 10 lodged upon the top of the horizontal flange when the rails are mounted with said flanges at the upper edge. In order to render the engagement of the side rail with the housing as rigid as possible, and for that purpose to permit the angle iron which forms the rail to abut squarely at its end against the inner end of the housing, the end of the inner side, 1^c, of the housing which projects past the forward vertical edge, 1^c,—necessarily 1 in order to permit the riveted connection of said vertical end with said inner side,—is provided with the angular notches, 16, 17, at the upper and lower corners of said projecting edge, said notches being adapted respectively to receive the horizontal flange of the side rail when the latter is applied with said horizontal flange at the top and when it is applied with said flange at the bottom, as described.

• To afford means for securing to the housing a cross rail of angle iron, as is customary and desirable, a vertical lug, 18, is struck out of the inner wall of the housing, and a horizontal lug is provided by forming on 1

the blank in which the housing is made, a tongue, 19, which in the completion of the housing is folded over across the cavity of the housing at the top thereof, engaged in a notch, 20, which is made in the upper edge of the inner wall, 1^c, of the housing, and projects inward beyond said inner wall in proper relation to the vertical lug, 18, to adapt the two lugs to seat respectively the two flanges of the transverse tie rail, F.

I claim:—

1. In combination with a corner post of a bed, a bracket housing for a bed side-rail tongue, having two opposite side walls between which the tongue may enter, and two vertical edge walls apertured to receive the tongue endwise; a stud projecting from one of said side walls across the path of the tongue proximate to one edge of said path; a tapered sleeve on said stud, and means for forcing the sleeve along the stud to wedge its tapered end against the proximate edge of the tongue.

2. In combination with a corner post of a bed, a bracket housing for a side-rail tongue, comprising two members, one of which is made of metal plate folded to form parallel inner and outer side walls and a vertical edge wall which projects from the end of one of the side walls, and is joined rigidly to the opposite side wall, the other member consisting of a staple-like device, the bridge of the staple being box-like, said staple-like device being engaged with the first mentioned member with the mouth of its box-like bridge facing away from said edge wall of the first member, said edge wall and the box-bottom having apertures in line for receiving the tongue thrust through them and across the space between them in the housing; a stud projecting from one wall of the housing across the cavity thereof, proximate to the path of inthrust of the tongue at one edge thereof, and protruding through the opposite wall of the housing, a tapered sleeve mounted on said stud and a nut on the protruding portion of the stud for crowding the nut there-along into the wedge engagement with the tongue.

3. In combination with a corner post of a bed, a bracket housing for a bed side-rail tongue, having two opposite side walls between which the tongue may enter, and two vertical edge walls apertured to receive the tongue endwise; a stud projecting from one of said side walls across the path of the tongue proximate to one edge of said path; a tapered sleeve on said stud, and means for forcing the sleeve along the stud to wedge its tapered end against the proximate edge of the tongue, the inner side wall of the housing having an aperture concentric with the stud of diameter suitable for admitting the tapered sleeve, said sleeve having an un-tapered portion which seats in said aperture

and slides therethrough in said wedging action.

4. In combination with a corner post of a bed, a bracket mounted rigidly thereon which constitutes a housing for a bed rail tongue, said housing having opposite side walls and edge walls, the latter having apertures alined for receiving the bed rail tongue, the bed rail having a tongue adapted to be thrust through said apertures for engagement with the housing; a stud mounted in one side wall of the housing and protruding through the opposite side wall and extending past the lower edge of the tongue proximate thereto; a tapered sleeve mounted for sliding on the stud and adapted by such sliding to be wedged under the lower edge of the tongue, the stud being threaded at its end which protrudes beyond the inner wall of the housing, and a nut on said protruding end for crowding the sleeve toward the tongue for wedging against the lower edge thereof, the tongue having a notch positioned for engagement of the tapered sleeve when the tongue is engaged with both the apertures of the housing.

5. In a bed frame, a housing for a side-rail tongue having longitudinal apertures for inthrust of the tongue; a tapering device mounted in the housing for wedge engagement with one edge of the tongue, and means for crowding such tapering device into such wedge engagement.

6. In a bed frame, in combination with a bed post and side rail, a housing mounted on the post for engagement of the side rail made of metal plate folded to form a tongue housing, and comprising inner and outer vertical side walls, the inner wall having a lug struck from it and folded about a vertical line inwardly so as to project in a vertical plane transverse to the side rail, the outer wall having a lug extending from its upper edge and folded at right angles to its wall across the housing, so as to lie in a horizontal plane and extend transversely of the side rail inwardly at right angles to the first mentioned lug, said lugs being relatively positioned for the engagement therewith of the vertical and horizontal flanges, respectively, of the transverse tie rail.

7. In a bed frame, in combination with a bed post and side rail, a housing mounted on the post for engagement of the side rail made of metal plate folded to form a tongue housing, and comprising inner and outer vertical side walls, the inner wall having a lug struck from it and folded about a vertical line inwardly so as to project in a vertical plane transverse to the side rail, the outer wall having a lug extending from its upper edge and folded at right angles to its wall across the housing, so as to lie in a horizontal plane and extend transversely of

- the side rail inwardly at right angles to the first mentioned lug, said lugs being relatively positioned for the engagement therewith of the vertical and horizontal flanges.
- 5 respectively, of the transverse tie rail, the upper edge of the said inner wall of the housing being notched for engagement of the horizontal lug therewith when folded to said horizontal position.
10. 8. In combination with corner posts having bracket housings mounted thereon, a side rail having at its opposite ends identically formed tongues adapted to be inserted into the housings, said tongues being symmetrical about a longitudinal medial line and having symmetrically positioned features for engagement of fastening devices in the housing, the housing having means forming a stop for one of its edges, and
- 15 means mounted in the housing for operating upon the opposite edge to force the first mentioned edge against such stop.
9. In combination with the bracket housings having opposed side walls, and edge walls having apertures horizontally aligned with each other; a bed rail having at its opposite ends similarly positioned and identically formed tongues adapted to enter the aligned apertures of the housing and having 20 symmetrically positioned notches in the upper and lower edges, and a locking device mounted in the housing adapted to engage the notch at one of said edges.
10. In a bed frame, in combination with a tongue side-rail, a housing having longitudinal apertures for intrust of the tongue; a tapering device mounted in the housing for wedge engagement with one edge of the tongue, and means for crowding said tapering device into such wedge engagement, the tongue having a notch in the said edge, positioned for engagement with the tapering device at the fully inserted position of the tongue in the housing.
15. 11. In a bed frame, in combination with a tongued side-rail, a bracket having side walls and an entrance between them for the side rail tongue, and two longitudinally separated stops for one edge of such tongue; a tapering device mounted in the housing for movement in the direction of its taper transversely of the tongue, positioned at the opposite side of the path of intrust of the tongue from said stops, and at a point along 25 said path intermediate said stops.
12. In a bed frame, in combination with a
- tongued side rail, a bracket housing having side walls and entrance between them for the side rail tongue; a stud mounted in one side wall and projecting transversely of the tongue past one longitudinal edge thereof; a sleeve mounted on said stud having a tapering end adapted to engage wedge-wise against the adjacent edge of the tongue; the stud having its end threaded, and a nut swiveled to the sleeve and screwed onto the stud for moving the sleeve endwise along the stud into and out of engagement with the tongue.
13. In combination with a corner post, a bracket of metal plate folded to form side walls and an outer edge wall, the latter being apertured to admit endwise a tongued rail terminal, the aperture having its outer vertical edge positioned in the plane of the inner surface of the outer side wall, and means in the housing for engaging the tongue to bind it against said side wall.
14. A bed corner bracket of metal plate folded to form side walls and an outer edge wall, the latter being apertured adjacent to one of the side walls; a bed rail having a terminal adapted to be inserted endwise through said aperture into the housing, said terminal having its upper and lower edges formed alike, the housing having means for stopping one of said edges against vertical movement, and means mounted in the housing for movement therein to cause it to engage the opposite edge for forcing the latter against the stop.
15. A bed rail corner bracket of metal plate folded to form side walls and an outer edge wall, the latter having an aperture adjacent to one of said side walls; a side rail having a terminal which is symmetrical about a longitudinal medial line, and has symmetrically-positioned irregularities in its upper and lower edges; the housing being provided with means for stopping one of said edges against vertical movement, and means mounted in the housing for movement therein for engagement with and disengagement from said irregularity of the opposite edge of the terminal.
- In testimony whereof, I have hereunto set my hand at Chicago, Illinois, this 30th day of July, 1913.
